UNITED STATES PATENT OFFICE

2,014,628

SHOE

George E. Musebeck, Danville, Ill., assignor to
Musebeck Shoe Company, Danville, Ill., a corporation

Application April 13, 1934, Serial No. 720,468

2 Claims. (Cl. 36—8.5)

This invention relates to a shoe and more particularly to a shoe designed to correct inrolling or pronation of a foot whose muscles have become too weak to support the arches of the foot in normal position.

In my prior United States Patent No. 1,916,198, issued July 4, 1933, I have shown a type of shoe and insole for the same purpose, in which the foot is made to roll outward by placing a greater thickness of insole material beneath the inner portion of the heel, thus straightening the foot by straightening the oscaitis and causing the weight of the body to fall upon the outer or cuboid portion of the longitudinal arch. By placing the corrective pressure beneath the heel, instead of beneath the instep as in prior practice, this pressure is applied at a point where there is no interference with the blood vessels and nerves which pass through certain openings between the bones. Normal blood circulation and nerve action are thereby maintained.

In the present invention the same result is attained by a different structure which presents several advantages over that illustrated in the said prior patent. The corrective pressure is applied by means of a pad of material placed above the normal insole instead of beneath the same. The pad is secured to the insole by cementing or stitching or both and requires no special channeling construction, the insole used being the same as that used for shoes designed for normal feet. The pad is preferably, but not always, formed of felt or other cushioning material which gives the corrective pressure in a yielding manner which still further prevents interference with blood circulation and nerve action.

Other objects and features of the invention will be understood from the accompanying drawing and the following description and claims:

Fig. 1 is a plan view of an insole having a corrective pad applied thereto in accordance with the invention. Fig. 2 is a sectional view of the same taken on the line 2—2 of Fig. 1. Fig. 3 is a sectional view of a completed shoe taken in a position corresponding to line 2—2 of Fig. 1. Fig. 4 is a sectional view of the disassembled insole and pad taken on the line 4—4 of Fig. 1.

In the drawing the insole 10 is of the same type ordinarily furnished for shoes for normal feet. It is provided around the greater portion of its periphery with a welt receiving recess 11 and the usual stitching channel cuts 12. A pad 13, preferably formed of a resilient material such as felt, is secured to the upper surface of the insole 10. Preferably it is cemented to said insole and is further secured by a line of stitching 14 passing

into the welt receiving recess 11. As will be seen from Fig. 1, the pad 13 extends rearwardly substantially to the rear of the heel and inwardly to the approximate center line of the insole 10. The pad extends forwardly slightly ahead of the breast of the heel. In the illustration shown, the pad 13 extends beyond the limit of the insole 10 to form an arch support extension. In many cases, however, this type of extension is not necessary and may be omitted.

In Fig. 3 the pad 13 is shown attached to the insole 10 and assembled in a completed shoe. The shoe is provided with an outsole 15, heel 16, welt 17 and upper 18 all assembled in the usual manner. A false insole 19 of thin, flexible leather is placed above the insole 10 and pad 13 to give a finished appearance to the interior of the shoe.

As will be apparent in Fig. 4, the pad 13 has its greatest thickness above the breast of the heel 20 of the shoe, the position of which is indicated by the arrow 20. From this point the pad slopes rapidly in all directions. The maximum pressure is thereby brought to bear on the inner corner of the heel and not beneath the instep, 25 At this point the interference with blood circulation and nerve channels is a minimum, so that corrective pressure applied thereto forces the foot to assume its normal position without danger of cramping either blood vessels or nerves.

While the foregoing description illustrates one form of the invention, it is obvious that details thereof may be varied without departing from the scope of the invention as defined by the appended claims.

The invention claimed is:

1. In a shoe, the combination of an insole, and a cushion pad secured to the upper surface of said insole, said pad extending beyond the inner edge of the insole to form an arch support extension, 40 extending inwardly substantially to the center line of the insole and rearwardly above the inner portion of the heel of the insole substantially to the rear edge thereof, said pad having its greatest thickness at the forward and inner portion of the heel.

2. In a shoe, the combination of an insole, and a cushion pad secured to the upper surface of said insole adjacent the inner edge thereof and extending inwardly substantially to the center line 50 of the insole, forwardly above the shank of the insole and rearwardly substantially to the rear edge of the heel of the insole, said pad having its greatest thickness at the forward and inner portion of the heel.
